DESIGN FOR A COMBINED CIGARETTE HOLDER, ASHTRAY, AND EXTINGUISHER

Harold E. Ridewood, Victoria, British Columbia,
Canada

Application July 17, 1935, Serial No. 57,699

Term of patent 3½ years

To all whom it may concern:

Be it known that I, Harold E. Ridewood, a citizen of the Dominion of Canada, subject of the King of England, residing at Victoria, British Columbia, have invented a new, original, and ornamental Design for a Combined Cigarette Holder, Ashtray, and Extinguisher, of which the following is a specification, reference being had to the accompanying drawing, forming part thereof.

I claim:

The ornamental design for a combined cigarette holder, ashtray, and extinguisher, as shown.

HAROLD E. RIDEWOOD.
